INVENTOR:

G. D. Melotte.

UNITED STATES PATENT OFFICE.

GABRIEL D. MELOTTE, OF UTICA, NEW YORK.

DESIGN FOR LASTS.

Specification forming part of Design No. **6,153**, dated September 24, 1872.

To all whom it may concern:

Be it known that I, GABRIEL D. MELOTTE, of Utica, in the county of Oneida and State of New York, have invented and produced a new and original Design for Shoemakers' Lasts, of which the following is a specification:

Figure 1 is a plan, and Fig. 2 an inverted, view of my last.

A represents the instep, which starts at a point corresponding to the center of the ankle and runs diagonally to the inside of the great toe; B and C, prominences made to correspond with the inner and outer sides of the foot in the usual manner. D is a prominence at the outside shank so as to correspond to a bone which is more or less developed in every foot. On the bottom of the last is still an-

other prominence, to correspond to the ball-joint of the foot. G is a prominence at the great toe.

Boots and shoes made from these lasts will be found much more comfortable and easy than those generally made, as every conformation of the foot is strictly followed.

Having thus described my invention, what I claim as new and for which I desire to secure Letters Patent, is—

The design for a last, substantially as set forth and shown.

GABRIEL D. MELOTTE.
